PAINT ROLLER

J. C. Davis, 9818 Hathaway, Dallas, Tex. 75220

Filed Apr. 8, 1970, Ser. No. 22,329

Term of patent 14 years

Int. Cl. D18—99

U.S. Cl. D64—18

The figure is a perspective view of a paint roller showing my new design, the side opposite being generally similar in appearance.

I claim:

The ornamental design for a paint roller, substantially as shown and described.
